(57) **CLAIM**

The ornamental design for a weather station clock, as shown and described.

DESCRIPTION

FIG. 1 is a top perspective view of a weather station clock showing my new design;

FIG. 2 is a front view thereof;

FIG. 3 is a rear view showing the weather station clock in an alternate configuration of use;

FIG. 4 is a left side view thereof;

FIG. 5 is a right side view thereof;

FIG. 6 is a top plan view thereof; and,

FIG. 7 is a bottom plan view showing the weather station clock in an alternate configuration of use.

The broken lines in the drawings depict portions of the weather station clock that form no part of the claimed design.

1 Claim, 7 Drawing Sheets
